DESIGN FOR A KNITTED FABRIC

Philip Rosenkrantz, Brooklyn, N. Y.

Application February 1, 1938, Serial No. 74,793

Term of patent 7 years

To all whom it may concern:

Be it known that I, Philip Rosenkrantz, a citizen of the United States, residing at Brooklyn, county of Kings, and State of New York, have invented a new, original, and ornamental Design for a Knitted Fabric, of which the following is a specification, reference being had to the accompanying drawing, forming a part thereof.

The figure is a plan view of a section of knitted fabric embodying my new design.

The knitted fabric of my design is characterized by spaced apart rows of drop stitches extending in the direction of the wales which give the fabric a corrugated appearance in combination with horizontal bands of contrasting knit and color as shown.

I claim:

The ornamental design for a knitted fabric, as shown and described.

PHILIP ROSENKRANTZ.
